HAT FORM

Emil John Feurer, Chicago, Ill.

Application February 6, 1933, Serial No. 655,438

2 Claims. (Cl. 223—25)

My invention relates to improvements in a hat form adapted for use particularly in the cleaning or brushing of hats, and which may be made in a plurality of sizes for use in cleaning various sizes and kinds of hats.

Another and further object of my invention is the provision of a hat form which is adapted to be used in the cleaning or brushing of hats and which is so fashioned that a hat can be placed inside of the form for the purpose of cleaning the inner part of the hat and the under side of the brim, or the form in its closed position can be inserted into a hat so that the outer side and brim of the hat can be cleaned or brushed against a firm body and the cleaning or brushing effectively performed.

Another and further object of my invention is the provision of a hat form which is of thin, light material, preferably of metal, and which can be easily and cheaply manufactured, will perform satisfactory service for an indefinite length of time, and which preferably is made in two sections, which sections are movably connected together to allow for the placing of a hat either inside of the crown portion or outside thereof, as may be desired.

These and other objects of my invention will be more fully and better understood by reference to the accompanying sheet of drawing, in which—

Figure 1 is an elevational view of the two sections forming my improved form;

Figure 2 is a side elevational view showing the form in its closed position, over which a hat may be fitted; and

Figure 3 is an elevational view showing the form in its extended position adapted to receive the crown of a hat.

Referring now specifically to the drawing, and in which like reference characters refer to like parts throughout, one of the sections 10 is shown, comprising a crown portion and a brim portion integrally formed therewith, and a corresponding portion 11 being shown in the cooperating hat form section, also comprising a crown and brim portion. A connecting member 12 is secured to the member 10 in any approved manner as by spot welding, and adapted to be secured on the under side of the member 10 adjacent the marginal edge thereof, and over which the marginal edge of the member 11 is adapted to slide so that when the form is in its closed position the edges of the members 10 and 11 meet in abutting relationship with each other.

Slots 14, 14 are provided in the member 12 for purposes hereinafter described, while each of the

sections 10 and 11 have rim portions which extend therearound and are integrally formed with the members 10 and 11, the rim portion on the member 11 has projecting end portions adapted to underlie the rim portion of the member 10 when the edges are placed in cooperative relation with each other. Short studs 17, 17 are provided which are welded into openings formed adjacent the marginal edge of the member 11 and are adapted to be received into the slots 14 in the member 12 and have heads thereon of slightly greater width than the slots 14, to securely hold the device in operation and prevent the separation of the two members, and also as means to limit the distance of separation of these two members when the sections are pulled apart for the purpose of allowing a hat to be placed inside of the sections for transportation, or cleaning the lower part of the brim and inside of the hat if desired.

In forming the device, which may be made preferably of pressed sheet metal or the like, the crown and rim portions of the device can be integrally formed by being pressed into shape, and the member 12 fitted to one of the portions afterwards, as may be desired. The sections are thereupon brought into cooperative relation with each other by fitting the edge of the member 11 over the fore portion of the face of the member 12. The studs 17, 17, which are exceedingly short, are then inserted through the slots 14, 14 in the member 12 and into holes previously formed in the member 11 adjacent the forward edge thereof and preferably are welded to this member. The members 11 and 12 can thereafter be pushed together for the purpose of placing a hat thereover or opened so that a hat may be placed inside the form.

In operation, the device is exceedingly simple in that when it is desired to clean a hat, particularly of the felt variety, on the outer side thereof, the form is closed and the hat placed over the form, which is of appropriate size to retain the hat in its proper shape and prevent wrinkling or creasing of portions of the felt. The hat can be cleaned on the outer side with a liquid cleaner, or brushed, as may be desired, the upper portion of the rim of the hat being cleaned at the same time. The hat is then removed from the form and the form opened to its extended position, whereupon the crown of the hat is placed in the crown of the form and the inside of the crown and the lower portion of the brim of the hat cleaned. The hat may be allowed to remain in the form or on the outer side thereof, if de-

sired, for purposes of transportation without possibility of the hat being crushed or otherwise distorted in shape.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination, a hat form comprising a pair of sections of thin, non-yielding material, each section having a crown and brim portion having substantially smooth inside and outside surfaces, the brim portions being in overlapped relation at each of their ends, a connecting member secured to one crown portion along one of its edges and having slots therein adjacent its

free edge, and fastening members fixedly mounted in the other crown portion adjacent the free edge thereof and extending through the slots in said connecting member, the said brim and crown sections being adjustably joined together.

2. In combination, a hat form comprising a pair of sections of thin, non-yielding material, each section having a crown and brim portion, the brim portions being in overlapped relation at each of their ends, a connecting member secured to one crown portion along its free edge having slots therein adjacent the free edge of the connecting member, and studs fixedly mounted in the other crown portion adjacent the free edge thereof and extending through the slots in said connecting member, the said brim and crown portions being movably joined together, both the inside and outside surfaces of the form being smooth and unbroken.

EMIL JOHN FEURER. 20
